(57) **CLAIM**

The ornamental design for an angular measuring scale, as shown and described.

DESCRIPTION

FIG. 1 is a top view of an angular measuring scale showing our new design;

FIG. 2 is a rear end view thereof;

FIG. 3 is a front end view thereof;

FIG. 4 is a left side view thereof;

FIG. 5 is a right side view thereof; and,

FIG. 6 is a bottom view thereof.

The measuring indicia shown in broken lines are exemplary only, and form no part of the claimed invention.
